SHAVER-CLIPPER

John W. Halterman, Los Angeles, Calif.

Application March 1, 1948, Serial No. 12,360

4 Claims. (Cl. 30—43)

1

The present invention relates to an improved shaver or hair clipper.

It is desirable that a shaver comprise a minimum number of parts, each of which may be made easily and readily assembled to form the composite structure. It is further desirable that the shaver requires little power to drive it whereby the electric motor coupled thereto may be of relatively small size to allow the composite shaver to be easily carried on a person and stored. Also, it is desirable that the relatively movable parts of the shaver move with a minimum amount of friction so as to develop a minimum amount of heat.

It is therefore an object of the present invention to provide an improved shaver whereby the above mentioned desideratum may be achieved.

Another object of the present invention is to provide an improved shaver in which the movable cutting element is a flat bar movable between spaced guides with a minimum amount of friction.

Still another object of the present invention is to provide an improved shaver incorporating a flat movable cutting element which may be easily and accurately assembled in operative position without the use of skilled personnel.

Usually, the movable cutting element of an electric shaver is spring biased into engagement with the other stationary cooperating cutting or shearing element and of necessity there is a relatively large pressure per unit area between the movable and stationary element. The use of such spring is usually to assure cooperation between the two cutting or shearing elements. In accordance with the present invention there is provided a new means whereby the two cutting elements may be adjusted and fixed in relative position with one another to provide suitable cutting, without the use of a spring, in which case the frictional resistance between the two cutting elements is greatly minimized.

A further object of the present invention is to provide a freely floating cutting element in a shaver positioned in cutting engagement with a cooperating cutter without the presence of a spring biasing the two cutting elements into engagement.

It is understood in the specification and the claims appended thereto that the term "freely floating" is thus used to designate the condition of my improved cutting elements into engagement with one another.

Still a further object of the present invention is to provide an improved shaver having a "freely floating" cutting element as specified.

Still another object of the present invention is to provide an improved shaver or clipper in which the movable cutter element may be driven at a relatively high speed by virtue of the fact

10 that no leverage is exerted on the movable cutter which would otherwise tend to cause it to bind.

Still another object of the present invention is to provide an improved shaver or hair clipper characterized by the fact that the cutting or shearing elements are mutually reversible in position so that efficient shaving or hair clipping is obtained depending upon the relative positions of such reversible cutter elements.

Yet another object of the present invention is to provide an improved shaver or clipper in which the relatively stationary and relatively movable cutter elements are maintained in operative relationship with respect to one another without the use of a spring biasing them together, which would otherwise produce unnecessary frictional forces, and without the danger of the presence of excessive tightening or clamping forces between the cutter members.

20 The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

25 Figure 1 is a view in front elevation of a portion of an electric shaver embodying the present invention.

Figure 2 is a view in end elevation of the same.

Figure 3 is a view in elevation of the back of the cutter head shown in Figure 1.

Figure 4 is a sectional view taken substantially on the line 4—4 of Figure 1.

Figure 5 is a view in perspective of the stationary portion of the shaver adapted to have mounted thereon the three elements shown in Figure 6.

Figure 6 is a view in perspective of the cooperating cutting elements and retaining member adapted for mounting on the unit shown in Figure 5.

Figure 7 and 8 are views in side and front elevation of a razor embodying the present invention drawn to scale.

Figure 9 is a perspective view of the razor shown in Figures 7 and 8.

Figure 10 is an enlarged sectional view taken substantially on the line 10—10 of Figures 3 and 8.

Figure 11 is a sectional view taken substantially on the line 11—11 of Figure 10.

Figure 12 is a sectional view corresponding to the sectional view shown in Figure 10 but with the position of the cutter elements reversed.

Figure 13 is a sectional view taken substantially on the line 13—13 of Figure 12.

The shaver or hair clipper is of the electric

type and may be driven by any conventional type of prime mover ordinarily found in commercial electric dry shavers in which a rod such as a rod 10 in Figure 5 is reciprocated at a relatively high speed. However, one important feature of the present invention is that such prime mover may be of relatively small size because the movable cutting element or blade 11 cooperating with the stationary cutting element or blade 12 is "freely floating."

The shaver head embodying important features of the present invention comprises essentially three elements; namely, the freely floating flat cutting element of metal disposed between the relatively stationary cutting element 12 and the adjustable retaining member 13. The stationary cutting element 12 may be permanently affixed to the platform or base 14 with the reciprocatable actuating bar or member 10 passing through the centrally disposed oval shape openings 15 therein and with the cutter 12 accurately positioned on the base 14 by the cooperation of the spaced abutments or upstanding lugs 17, 18 on the base 14 which are snugly received within the rectangular notches 19 and 20 respectively in the cutter 12 and which projects upwardly into the slightly enlarged notches 21, 22 in the movable cutter 11 to guide the same in its movement by the reciprocatable member 10 which is disposed snugly in the centrally located aperture 23 in cutter 11.

The movement of the cutter 11 is guided essentially by the guide abutments 17, 18 and is prevented from moving in a direction perpendicular to its plane by the other cutter 12 and the retaining member 13 between which the cutter 11 is sandwiched. While adjacent faces of the flat cutting elements 11 and 12 are in contact with one another, the adjustable retaining member 13 has a downwardly disposed lip of limited contact area immediately opposite the adjacent upper face of the cutter 11 to minimize frictional forces.

In the assembly of the elements shown in Figure 6, the cutter 12 may be releasably mounted on the base 14 as indicated or it may be affixed thereto in a more permanent manner, for example, by means of countersunk head screws screwed into the base 14. After the cutter 12 is mounted in position with the reciprocable element 10 passing through the clearance aperture 15 the movable cutting element 11 and retaining member 13 are in turn mounted in position. An important feature of the present invention is the structure and features produced by the adjustable retaining element 13. This retaining element 13 is substantially L-shaped for mounting in the transversely extending slit 14A of the base member by clamping screws or fastening means 25, 26 passing through corresponding notches 27, 28 in the retaining member 13 in such a manner as to maintain the flat bearing surface 29 in spaced relationship to the movable cutter 11 or the cutter 12 in Figure 12. If this spacing is in the order of a small fraction of a .001 of an inch the shaver or clipper, as the case may be, would still be effective. For example, with the fastening screws 25, 26 released, the retaining member 13 is moved adjacent the cutting element 11 either with the finger or under the influence of gravity forces on such retaining member and at the same time the fastening screws 25, 26 are tightened. In such cases, the resulting spacing between the bearing surface 29 on the retaining member and the adjacent flat face of the cutter 11 even though a small fraction

of a .001" would still be sufficient for satisfactory operation. An important feature is that the particular means by which the retaining member 13 is maintained on the base avoids or prevents the existence of excessive force between the cutters 11, 12. The retaining member 13 is held by screws 25, 26 which exert a force on the retaining member in a direction substantially parallel to the planes of the cutters 11, 12 so regardless of the degree in which the screws 25, 26 are fastened, the force between the retaining member and the cutting element 11 or 12, as the case may be, remains the same i. e. substantially zero. In order to prevent loosening of the set screws 25, 26 in operation of the shaver, preferably these screws are maintained in locked position by the locking means provided by the face 14B of which serves as a resilient cantilever member through which the set screws pass. Thus, the resilient cantilever portion 14B is deflected a slight amount to apply frictional forces on the threads of the screws to releasably lock them in place.

Preferably, as shown in Figure 10, the bottom relatively stationary cutting element 12 projects outwardly a slight distance greater than the movable cutting element 11 and both cutting elements are each provided with a serrated chamfered edge so that whiskers or hair disposed in the serrations of such edges is sheared or cut off in operation of the shaver.

Figures 7, 8 and 9 show in actual physical size a shaver incorporating the cutting elements described in the previous figures. Figure 10 shows in enlarged form the position of the cutter members 11 and 12 when the device is intended for use as a shaver while Figure 12 shows the same elements reversed only with respect to the other when the device is intended for use as a hair clipper. In the elements shown in both Figures 10 and 12, the cutter 11 in each case is moved by the actuating member 10 while the other cooperating cutter member 12 is maintained relatively stationary due to engagement of the apertured portions 19 and 20 therein with the abutments 17, 18.

The cutter elements 11 may have a thickness on the order of .012". The cutter element 12 may have a thickness of .015". The teeth in the serrated edges of members 11 and 12 may have a thickness of .008" with the slit distance between teeth of .007". The blade holder 13 from its forward edge 31 to its back face 32 may be 1". An important feature of the present invention is that the blade holder 13 cannot cause excessive forces to be exerted between the cutter elements 11 and 12 either in the element shown in Figure 10 or in the element shown in Figure 12. This feature results from the particular manner in which the blade holder 13 is fastened by means of the screws 25, 26 to the stationary base 14. The particular manner in which the blade holder 13 is fastened thus assures the absence of excessive clamping forces and avoids abuse. While I have described above a clearance of a small fraction of a .001" between the retaining member 13 and the adjacent cutter member it is, of course, possible that even with such small tolerance, substantially no frictional forces are developed therebetween.

While the particular embodiments of the present invention have been shown and described, it will be obvious to those skilled in the art that changes and modifications may be made without departing from this invention in its broader as-

pects and, therefore, the aim in the appended claims is to cover all such changes and modifications as fall within the true spirit and scope of this invention.

I claim:

1. In an electric shaver, a flat elongated base, upstanding end lugs on the base, superimposed stationary and movable blades on the base, the stationary blade having end notches to fit the lugs laterally and whose inner ends are spaced apart substantially the same as the spacing between the adjacent ends of the lugs so as to prevent longitudinal and lateral displacement of said blade on the base and the movable blade having longitudinally elongated lug-receiving end notches whose width is substantially the same as that of the lugs but whose ends are closer to each other than the adjacent ends of the lugs whereby to allow of longitudinal movement of said movable blade while holding the same against transverse movement, and a retaining member removably mounted on the base behind the blades and including a lip overhanging the uppermost blade for substantially the full length thereof to prevent separation of the blades.

2. In an electric shaver, a flat elongated base, superimposed stationary and movable blades on the base, lugs upstanding from the base and projecting through notches in the stationary blade and cooperating with the walls of said notches to hold the stationary blade against movement on the base, said lugs also projecting through notches in the movable blade and cooperating with the walls of such notches to permit said movable blade to reciprocate longitudinally of the base; and a blade retaining member of L-shaped form in section and comprising a leg removably secured against the back of the base below the blades and upstanding past the back edges thereof in contact therewith and from end to end thereof, and another leg overhanging and substantially engaging the uppermost blade, the first named leg having horizontally spaced vertical slots, and headed screws bearing against said first named leg and projecting through the slots and threaded into the base at the back.

3. In an electric shaver comprising a flat base, a pair of flat cooperating cutting blades separate from and invertible as a unit relative to the base, elements on the base projecting through notches in the blades, the walls of the notches of one blade cooperating with the elements to hold said blade stationary on the base and the walls of the notches in the other blade cooperating with the elements to permit of longitudinal reciprocating movement of said other blade, and a retainer mounted on the base including a rigid element overhanging the outermost blade to releasably hold the blades against separation from each other and from the base; the shaver including blade reciprocating means.

4. In an electric shaver having a base, a longitudinally oscillatable driving stem projecting from the base intermediate its ends, and a pair of cooperating blades separate from and mounted on the base for relative reciprocation and invertible as a unit relative to said base; one blade having an opening which fits over the stem in driving relation and the other blade having a longitudinal slot to receive the stem in clearance relation irrespective of the position of said stem; the latter projecting upwardly from the base a distance not less than the thickness of the two blades.
